UNITED STATES PATENT OFFICE.

ANDREW J. NICHOLAS, OF PHILADELPHIA, PENNSYLVANIA, ASSIGNOR TO A. D. COOK, INCORPORATED, OF LAWRENCEBURG, INDIANA, A CORPORATION OF INDIANA.

DEEP-WELL POWER PUMP.

Application filed October 23, 1922. Serial No. 596,407.

To all whom it may concern:

Be it known that I, ANDREW J. NICHOLAS, a citizen of the United States, residing at Philadelphia, in the county of Philadelphia 5 and State of Pennsylvania, have invented new and useful Improvements in Deep-Well Power Pumps, of which the following is a specification.

This invention relates to pumps, and particularly to double stroke deep well pumps, and one of the objects is to produce a device of this nature in which the structure may be very compact, requiring comparatively small head room.

Another object is to produce a new and improved form of cross-head whereby the two cross-heads may operate simultaneously in opposite directions and without interference with each other or with the operating members therefor, and whereby the angularity between the plane of movement of the cross-head and the axis of the operating links may be minimized.

Another object is to construct a device of this nature so that the mechanism in the well may be quickly and easily removed and without the necessity of moving the base and principal superstructure.

Another object is to provide a new and improved operating mechanism whereby an even and steady impulse may be given the moving parts.

Another object is to make many of the parts interchangeable so that the design may be standardized, and more quickly and cheaply produced and assembled.

Another object is to bring the point of applying the power low in the construction so as to render it more stable and efficient.

With these and other objects in view as will more clearly appear hereinafter, the invention consists of certain novel features of construction and combination and arrangement of parts, the essential features of which are hereinafter fully described, are particularly pointed out in the appended claims, and are illustrated in the accompanying drawing, in which:

Figure 1 is a front elevation of my improved pump.

Figure 2 is a side elevation of the same.

Figure 3 is a fragmentary sectional view taken substantially on line 3-3 of Figure 2.

Figure 4 is a detail perspective view of the upper cross-head.

Figure 5 is a similar view of the lower cross-head.

Like characters of reference refer to like parts in all views.

Referring to the drawing in detail, 10 indicates the usual T-fitting which is the outlet head for the well, the water being expelled through the side opening as is well understood in the art. Mounted for movement in the member 10 are the usual 60 tubular and rod plungers 11 and 12, the plungers (not shown) being of the over-lap type which are well known in the art and which serve the purpose of having a continuous flow of water even at the slowest speed. 70 It is to be borne in mind that it is desirable that the speed be slow and that the stroke be comparatively long. A closure member 13 is secured to the top of the T 10 in any suitable manner and forms a suitable bearing 75 for the plunger rod or tube 11.

The frame-work of the pump itself comprises a base portion 14 which may be set upon and bolted to any suitable foundation or supporting means, and removably supported side members 15 and 16 which carry at their top a head-frame 17 securing the members 15 and 16 together. The various portions of the frame may be bolted or otherwise secured. Extending from the head-frame 17 at opposite sides, are brackets 18 which form the upper seats for guide rods 19, the lower ends of which are suitably supported in bosses 20 formed on the upper face of the member 13. 80

Slidably mounted upon the rods 19 are the upper and lower cross-heads 21 and 22. These cross-heads form an important part of the present invention, and will now be described in detail. Each of the cross-heads is constructed in the form of the letter E and is provided with removable and interchangeable sleeves 23 for sliding engagement with the aforesaid guide rods 19. The sleeves are preferably made as shown in halves, being split longitudinally so that they may be connected to or disconnected from the guide rods without the necessity of removing the guide rods from the frame. There is also a central member 24 which is adapted to receive and hold its respective one of the plunger rods 11 or 12. In the case of the upper cross-head pivot studs 25 are secured to the central member 24; while in the case of the lower cross-head 22 pivot studs 26 are 95 100 105 110

secured to the sleeves 23, the latter being formed with reinforcing bosses 27 for this purpose.

Secured to the upper cross-head 21 are a pair of operating links 28, the same being connected pivotally on the studs 25 above mentioned, and extending downwardly therefrom. Similarly connected to the studs 26 are a pair of links 29 which extend upwardly therefrom.

It is desired at this point to call particular attention to the fact that the E-shaped construction of the cross-heads permits the links 29 to extend from the lower cross-head upwardly through the upper cross-head, and the lower links 28 to extend from the upper cross-head downwardly through the lower cross-head without interfering in any way with the operation of any of these parts. 20 This is clearly illustrated in Figure 1.

Mounted in bearings in the frames 15 and 16 and extending transversely therebetween, are shafts 30 and 31. Mounted upon the shaft 30 is the lower lever beam 32 and similarly mounted upon the upper shaft 31 is the upper lever beam 33, these parts being duplicates of each other but reversed in their position as shown clearly by the dotted lines in Figure 2. Secured to the lower arm 30 of the lever beam 32 and removable therefrom is an extension member 34 which is bifurcated as shown in Figure 1, its arms 35 being connected pivotally to the lower ends of respective links 28. A similar extension member 36 is secured to the upper arm of the lever beam 33 and has its arms 37 connected pivotally to the upper ends of respective links 29. The reason why the members 34 and 36 are made separable from the lever beam is so that they and the mechanism which is directly in the well may be removed without the necessity of moving the frame or any of the parts hereinafter described and which constitute the 40 operating mechanism of the device.

The device may be driven from any suitable source of power, and for the purpose of receiving this power, a gear 38 is mounted on the end of a shaft 39, said shaft being supported in split bearings 40 mounted on the side frames 15 and 16. A pair of gears 41 are secured to the shaft between the frames 15 and 16, and mesh with respective gear wheels 42 mounted on stub shafts 43, said shafts 43 being journaled in split bearings 44 in the side frames of the machine. The gears 42 are secured to each other by a crank pin 45 having its opposite ends extending through and secured to respective wheels 42. Between the two wheels 42 there are mounted on the crank pin 45 a pair of cross-head blocks 46 and 47, the cross-head

block 46 is adapted to slide along a way 48 provided for it in the upper lever beam 33 and block 47 along a way 49 in beam 32, and in consequence as the wheels 42 rotate, the pin 45 by moving the cross-head blocks 46 and 47 along the ways 48 and 49 will cause an oscillation of the lever beams 32 and 33 and a consequent upward and downward movement of the links and cross-heads connected thereto, and of the members 11 and 12.

It will be noted that with this form of operating mechanism when one of the cross-heads is drawn upwardly the other is moved downwardly and vice versa so that the cross-heads move on the guide rods 19 toward and from each other.

While I have described what I deem to be the most desirable embodiment of my invention, I do not limit myself to the specific details of construction of material, nor to anything less than the whole of my invention as defined in the appended claims.

What I claim:—

1. A pump comprising a plurality of E-shaped cross-heads, guide rods common to said cross-heads, links for operating said cross-heads, the respective links of each cross-head passing through another of said cross-heads, and means for operating said links.

2. A pump comprising a plurality of cross heads, guide rods common to said cross heads, links for operating said cross heads, the respective links of each cross head passing through another of said cross heads, a pair of gear wheels, a crank pin supported between said gear wheels and connected to said links for operating them, and means for rotating said gear wheels.

3. A pump comprising a plurality of cross heads, guide rods common to said cross heads, links for operating said cross heads, the respective links of each cross head passing through another of said cross heads, a pair of gear wheels, a crank pin supported between said gear wheels and connected to said links for operating them, a driving shaft and gears operable by said driving shaft and meshing with said first mentioned gears for operating the gears and links.

4. A pump comprising a plurality of cross heads, guide rods common to said cross heads, links for operating the cross heads, the respective links of each of said cross heads passing through another of said cross heads.

In testimony whereof I affix my signature.

ANDREW J. NICHOLAS.
